(57) **CLAIM**

The ornamental design for a bed and crib frame, as shown and described.

DESCRIPTION

FIG. 1 is a top perspective view of a bed and crib frame showing my new design;

FIG. 2 is a top plan view thereof;

FIG. 3 is a front elevation view thereof, and

FIG. 4 is a side elevation view thereof, the opposite side being a mirror image thereof.

FIG. 5 is an enlarged sectional view taken along line 5—5 of FIG. 3;

FIG. 6 is an enlarged sectional view taken along line 6—6 of FIG. 3;

FIG. 7 is an enlarged sectional view taken along line 7—7 of FIG. 3;

FIG. 8 is an enlarged sectional view taken along line 8—8 of FIG. 3; and,

FIG. 9 is an enlarged sectional view taken along line 9—9 of FIG. 3.

The rear and bottom views (not shown) form no part of the claimed design.
